UNITED STATES PATENT OFFICE.

PHILIP BOSTROM, OF GOODING, IDAHO.

HARNESS TRACE SUPPORT AND ASSEMBLY.

Application filed August 26, 1922. Serial No. 584,467.

To all whom it may concern:

Be it known that I, PHILIP BOSTROM, a citizen of the United States, residing at Gooding, in the county of Gooding and State of Idaho, have invented certain new and useful Improvements in a Harness Trace Support and Assembly, of which the following is a specification.

This invention relates to a harness trace support and assembly and particularly to structure to be used in conjunction with the back band or back straps and the belly-band billet of a truck or work harness to prevent wearing or chafing of the traces.

An object is to provide a structure of this character which will allow the trace to work freely, thus preventing wear and tear on the traces, and which will permit ready vertical adjustment of the trace.

A further object resides in so constructing the parts that the belly-band billet connects the combination and can be connected and adjusted without the customary stitching.

A still further object is to provide buckle and supporting loop portions, each provided with a broad flat wear surface, adapted to be used on the bottom and top edges of the trace to prevent wear.

With these and other objects in view, which will be apparent from the drawings, specification and claims, this invention includes certain novel features of construction and combinations of parts which will now be set forth.

In the drawings:

Figure 1 is a view in perspective showing my invention embodied in a harness.

Fig. 2 is an enlarged detail to better show the fitting of the parts.

Fig. 3 is a vertical sectional view on line 3—3 of Fig. 2.

Fig. 4 is a detail perspective showing the supporting loop.

Fig. 5 is a perspective view to show the construction of the buckle.

Fig. 6 is a view similar to Fig. 3, showing a modified construction of the device.

Fig. 7 shows the modified form of the buckle.

Fig. 8 is a perspective view of the modified form of supporting loop.

Fig. 9 is a view similar to Fig. 1, showing the adaptation of the structure to a different type of harness.

Fig. 10 is an enlarged detail of this mounting.

Fig. 11 is a vertical section through the parts illustrated in Fig. 10.

Fig. 12 shows the supporting loop in perspective.

Fig. 13 is a perspective view of the form of buckle employed on the bottom edge of the trace in the showing in Fig. 9.

Fig. 14 illustrates another modified form of supporting loop.

In Fig. 1, I have shown the invention applied to a truck or work harness having a back pad, but it will be understood the parts can be used upon other standard forms of heavy harness, and can be fitted with equal facility.

The buckle A, as best shown in Fig. 5, comprises the side bars 1 and 2, which are connected by cross-bars 3, 4 and 5. At their lower ends the bars 1 and 2 form a substantially triangular loop 6, and at their upper ends the side bars extend forwardly, then downwardly. A top cross spreader or wear-bar 7 and a front cross bar 8 are connected between the forwardly and downwardly disposed portions. A tongue 12 is provided on bar 4.

Extensions 9 and 10 are provided on the side bars 1 and 2, and a cross bar 11 extends across between their ends in front and substantially parallel with the bar 5. While I have designated the various portions of the buckle separately, it will be appreciated that in practice this buckle will doubtless be a single casting.

The supporting loop B, as best shown in Fig. 4, consists of the wear bar 13 flattened on its lower side and rounded up at its ends, and the loop 14 connected adjacent the ends of the bar and having its body substantially parallel with the middle portion of the bar. The bar is of slightly greater width than the thickness of the trace with which it will be used, and the loop 14 is sufficiently spaced to loosely accommodate two harness straps passed therethrough. A tongue 15 is provided on the bar and is sufficiently long to hold the bar when fitted in an opening punched in one of the straps passed through the loop.

In the use of my improved structure, many types of harness can be employed, but the construction shown in Fig. 1 has been found satisfactory. The traces 16 have

the guide straps 17 secured thereon, these side straps being of sufficient length to permit forward and back play for self-adjustment of the parts while the horse on which the harness is fitted is working. The back pad or saddle 18 is of usual construction, and the pad strap 19 depends therefrom. The remaining portions are of usual construction.

10 The strap billet 20 is passed through the loop 14 and has an opening punched to take tongue 12 so that the strap is held in place. One end of the strap is passed down through the loop formed by the guide strap 17 and the other end is brought down adjacent the inner side of the trace. The free ends of the strap 20 are then inserted in the buckle on opposite sides of the spreader bar 7, and tongue 12 is caught in openings 25 punched in each end of the strap. Bars 3 and 8 hold the strap in proper relation with respect to spreader bar 7 and the end 21 is tucked under bar 11 to thus insure that the ends will not become accidentally dis- 20 placed from the tongue 12.

The end of the pad strap 19 is passed through the loop 14 and is looped back and secured by buckle 22.

30 The belly-band 23 is provided with a buckle 24 in which the end 21 of strap 20 is adjustably held, or a snap hook can be provided on the end of the belly-band to be caught in the loop 6 of the buckle.

35 With this assembly of the parts, bar 13 presents a smooth surface on the top edge of the trace, and bar 7 will prevent chafing on the lower edge, these two bars spreading the sides of the billet sufficiently to clear the sides of the trace. Guide strap 17 limits 40 movement of the strap 20 along the trace, but at the same time allows sufficient forward and back play for self-adjustment of the parts while the horse is working.

45 In the modified construction shown in Figs. 6 to 8, the buckle C has a spreader or wear bar 25 extending across the top of the two sides 26 and 27, and these sides terminate in loop 28 at their lower ends. Cross bar 29 is provided on the other side adjacent the top of the sides, and cross-bars 31 and 32 are adjacent the top and bottom of the side portions on the inner side. Cross bars 33 and 34 are located on the outer and inner sides in staggered relation and are provided 50 with tongues 35 and 36 on their inner faces.

55 The supporting loop D, as shown in Fig. 8, comprises the bar 37, which has sides 38 and 39 depending therefrom and rolled out at their edges, and a loop 40 carried on the top of the bar.

60 In the use of this form of the structure the straps of the harness are assembled in much the manner set forth above except that the billet strap is held in place on the bar 65 37 by the rolled edges of the sides 38 and

39 of loop D, and one end of the strap is held by tongue 35 of buckle C, while the remaining end is retained by tongue 36. The bar 37 and sides 38 and 39 guard against chafing on the top and sides of the 70 trace, and spreader bar 25 will prevent undue wear on the lower edge of the trace.

In the showing in Figs. 9 to 13, the supporting loop E is adapted to be used without a back pad, this loop having a ring 41 75 in which the lead-up 42 and turn-back 43 are connected. The loop includes the side portions 44 and 45 associated with the ring and having the spreader or wear bar 46 extending therebetween. Front and back 80 bars 47 and 48 are extended parallel with and spaced from the bar 46, and a cylindrical cross-bar 50 is provided intermediate these bars. A tongue 51 is provided on cylindrical bar 50, and the back bar 48 has 85 rivet-receiving openings 52 therethrough. A leather shield 53 is held in the back of the supporting loop by rivets 54 clinched in openings 52, to prevent chafing of the horse.

The buckle F is somewhat similar to that 90 shown in Fig. 1, and includes side portions 55 and 56 terminating at their lower ends in a snap-receiving loop 57. A spreader and wear-bar 58 is provided across the remaining ends of the side portions, and side 95 bars 59 and 60 are connected between these side portions on the forward and rear sides of the buckle to be parallel with and spaced from the bar 58. An intermediate bar 61 is connected between the sides and spaced from 100 the side bars; and studs 62, or a bar, are provided at the inner extremity of the loop. The bars 59 and 61 have tongues 63 and 64 on their forward sides.

In assembling the loop E and buckle F 105 for use, the belly-band billet 65 is fitted between the various bars, in the manner shown in the drawings, to dispose the loop with its wear bar 46 adjacent the top edge of the trace 66 and the buckle has its wear bar 58 adjacent the lower edge of the trace. These bars also spread the intermediate portions of the billet strap to clear the sides of the trace. Tongues 63 and 64 secure the ends 110 of the billet strap, and tongue 51 is fitted through an opening in the bight of the billet to positively hold the loop against shifting.

The supporting loop G, as shown in Fig. 14, is a modification of the loop E, to better adapt the same for use with a back pad as 115 shown in Fig. 1, although it will be appreciated that the loop E might be used in this connection also. The sides 67 and 68 of this modified form have a spreader or wear bar 69 joining two of their extremities and a 120 supporting bar 70 connecting the remaining ends. Side bars 71 and 72 are provided on the front and back edges of the sides, and a cylindrical intermediate bar 73 is provided 125 between and parallel with bars 69 and 70. 130

This bar 73 has a tongue 74 on its upper side. The loop G has the billet fitted therethrough in much the manner shown in Fig. 11, only the strap-holding stud is on top of the bar, and the back pad strap is connected around bar 70. In some uses this tongue 74 may not be necessary.

While in the foregoing I have shown and described specific constructions and mountings, it will be appreciated that changes and modifications may be resorted to in the form and arrangement of the parts without departing from the spirit and scope of my invention.

Having thus described my invention, what I claim and desire to secure by Letter Patent is:

1. In combination with a belly-band billet strap, a belly-band billet buckle securing the ends of the strap provided with a bearing portion to slide on the lower edge of a trace, and a supporting loop provided with a bearing portion to slide on the top edge of the trace.

2. In combination with a strap forming a trace loop, a buckle securing said strap in loop form, and a supporting loop fitted to said strap, said buckle and loop having broad flat wearing portions to engage the edges of the trace.

3. In combination with a belly-band billet strap, doubled back to form a trace loop, a buckle securing the ends of said strap to preserve the loop form, and a supporting loop fitted in the double back portion of the strap provided with a loop for supporting attachment to portions of a harness, said buckle and loop having broad flat wearing bars to engage the edges of a trace and to spread the sides of the trace loop to clear the trace.

4. In combination with a trace and belly-band billet of a harness, said billet being folded over to form a trace loop, a buckle securing the ends of said looped belly-band billet and having a spreader-bar disposed between said ends to present a broad flat wearing surface at the lower edge of a trace fitted through the loop, and a supporting loop carried by portions of the harness fitted in the bight of the looped strap provided with a wear bar presenting a broad flat surface at the top edge of the trace.

5. In combination with a belly-band billet strap folded over to form a trace-receiving loop, a supporting loop having a spreader bar fitted in the bight of the looped strap and provided with a loop for attachment on portions of a harness, a buckle having a spreader-bar received between the ends of the billet strap and provided with cross-bars engaging with the strap to re-

tain the same in place within the buckle and in its looped form.

6. In combination, with a harness including a belly-band billet strap looped to support a trace and portions to support the loop, a buckle having a transverse spreader bar fitted between the ends of said strap to present the bar adjacent the lower edge of the trace and provided with cross-bars engaging the ends of the strap to retain its looped form, and a supporting loop carried by the supporting portions of the harness fitted in the bight of the billet strap and provided with a spreader bar disposed adjacent the upper edge of the trace.

7. A harness trace support and assembly comprising, with a strap forming a trace loop, a buckle in which the ends of said strap are secured provided with a broad flat wear bar to engage the lower edge of a trace fitted through the loop, and a supporting loop carried by portions of the harness fitted in the bight of the trace loop and provided with a spreader bar presenting a broad flat wear surface of the top edge of the trace.

8. In combination with a belly-band billet strap forming a trace loop, a buckle including side portions provided with a spreader bar to be fitted between the ends of said billet strap and provided with cross-bars disposed to retain the strap in position adjacent the spreader bar, and tongues on said cross-bars to engage and secure the ends of the strap.

9. In a harness trace support and assembly, a buckle having side portions terminating at their lower extremities in a loop to receive a snap hook, a spreader bar extending across between the side portions at their upper ends and presenting a broad flat outer surface, cross bars on each side of the spreader bar extending parallel and spaced therefrom, and a cross-bar intermediate the spreader bar and loop provided with a strap holding tongue.

10. In a buckle for use in a harness trace support and assembly, the combination with side portions terminating at their lower extremities in a loop adapted to receive a snap hook, a spreader bar extending across between the side portions at their upper end and presenting a broad flat outer face, the cross-bars on each side of the spreader bar spaced to receive strap ends and to confine the same closely adjacent the spreader bar, and other cross-bars having strap-holding tongues to engage with and secure strap ends fitted between the spreader bar and side bars.

In testimony whereof I affix my signature.

PHILIP BOSTROM.
